UNITED STATES PATENT OFFICE

SYDNEY FRANK WESTON, OF EAST PUTNEY, LONDON, ENGLAND, ASSIGNOR TO THE BABCOCK & WILCOX COMPANY, OF BAYONNE, NEW JERSEY, A CORPORATION OF NEW JERSEY

BOILER GAUGE

Application filed October 21, 1925, Serial No. 63,856, and in Great Britain January 10, 1925.

This invention relates to improvements in water gauges by which the height of the normal level of the water can be marked so that it can be readily seen.

5 The invention will be understood from the description in connection with the accompanying drawings, in which Fig. 1 is a side elevation of the gauge glass column with reflector attachment; Fig. 2 is a section along 10 the line 2—2 of Fig. 1; Fig. 3 is a front view, partly broken away; Fig. 4 is a horizontal section through one of the details; and Fig. 5 is a side view of the same.

In the drawings, reference character 10 indicates a water gauge glass of a common type that is connected to the steam and water spaces of a boiler by the connections 11 and 12, respectively. A series of reflectors 13 are superposed, one above the other, and are 20 mounted on a framework so as to be juxtaposed to the glass 10. Each one of the reflectors 13 comprises a portion 15 in the form of half of a truncated cone, with the edges of their lower portions 14 bent around rods 17 25 on each side, which rods constitute a portion of the framework for supporting the reflectors. The framework also comprises side walls 18 which prevent ingress of light from the sides. The framework is pivoted at 19 to 30 the hook 20 so that it can swing backwards in case the glass 10 bursts, thus receding from the glass, and also for the purpose of enabling the glass to be renewed. The framework is along its rear side, or along the 35 side opposite the glass 10, and a reflector 21 is mounted at this rear side. The reflector may contain an electric light and is adjustable in a vertical direction by means of the nuts 22 which contact with the respective sides of the 40 projection 23. The framework, side walls 18, the series of reflectors 13 and the reflector 21 may be considered broadly as a housing for the series of light.

One of the reflectors 13 has its ends which 45 bend around the rods 17 prolonged, as shown at 24 (Figs. 2, 4 and 5) and is slit, as shown at 25. The slit portion is provided with a hole 26 and the opposing portion is provided with a hole 27, these holes being for the purpose of receiving and retaining a glass button

or bead 28 that is spring held by virtue of the slit end 24. The bead may consist of a shank portion to extend through the holes and enlarged head portion.

When a light shines in the reflector 21 the rays therefrom pass between the skirt portions 15 of the reflectors 13 and illumine the gauge 10. The light cannot escape along the sides of the gauge 10 because the upright or vertical portions 14 contact with each other and form a wall. The rays, however, which strike the glass bead 28, which are preferably colored, pass through the same to a sufficient extent to cause the same to be readily visible. Markers consisting of beads or buttons similar to the one described, may be mounted in the vertical portions 14 of other reflectors 13 to mark the maximum and minimum safe heights of the water lever in the 70 boiler.

While I have illustrated and described one particular form of a gauge glass device and associated marker means, I do not wish to be limited thereto and reference is made to the following claims to indicate the scope 75 of my invention.

I claim:

1. In a water level indicator, a plurality of superposed inclined plates at one side of said indicator, and a light-transmitting medium mounted for illumination by rays of light passing between some of said plates.

2. In a water level indicator, a plurality of superposed plates one of which has a bore, a light-transmitting marker mounted in the bore in one of said plates and a source of light located at one side of said plates and passing between some of said plates for illuminating said marker.

3. In a water level indicator, a plurality of superposed inclined plates at one side of said indicator, said plates having parallel rim portions there being a bore through one of said rim portions and a light-transmitting medium mounted in said bore through one of the rim portions of said plates for illumination by rays of light passing between some of said plates.

4. In a water level indicator, a plurality of superposed inclined plates located at one

side of said indicator, said plates having parallel rim portions, there being a bore through one of said rim portions and a light-transmitting marker located in said bore as and for the purposes described.

5. In a water level indicator, a plurality of superposed inclined plates at one side of said indicator, said plates having parallel rim portions, one of which has a bore, a piece 10 of glass extending through the bore in said rim portion and yieldable means resiliently holding said glass in assembly with said rim portion.

6. In a water level indicator, a plurality of 15 superposed inclined plates located at one side of said indicator, said plates having parallel rim portions, there being a light-transmitting bore through one of said rim portions at the height of the normal water level and a glass 20 marker located in said light-transmitting bore.

7. In a water level indicator, a gauge glass, 25 a source of light positioned behind the gauge glass so as to illuminate the same, means interposed between said gauge glass and said source of light to direct rays of light toward said gauge glass and light-transmitting marker means located laterally to one side of the gauge glass and at a predetermined 30 water level with relation to the gauge glass and illuminated by light rays from said source of light.

8. In a water level indicator a gauge glass, 35 a source of light positioned behind the gauge glass so as to illuminate the same, fixed illuminated marker means located laterally to one side of the gauge glass, means supporting the illuminated marker means so that it may be illuminated by the source of light whereby 40 the relation of the liquid in the gauge glass may be determined with regard to a given point.

SYDNEY FRANK WESTON.
